HAIR DRYER

Robert J. Reading, Stratford, Conn., assignor to General

Electric Company, a corporation of New York
Filed Mar. 11, 1963, Ser. No. 73,920

Term of patent 14 years

(Cl. D86—10)

Fig. 3.

Fig. 4.

Fig. 5.

Fig. 6.

FIG. 1 is a front perspective view of a hair dryer embodying my new design;

FIG. 2 is an enlarged top plan view of the hair dryer with the cover removed;

FIG. 3 is a front elevational view of the cover of the hair dryer;

FIG. 4 is a front elevational view of the assembly shown in FIG. 2;

FIG. 5 is a rear elevational view of the cover shown in FIG. 3;

FIG. 6 is a rear elevational view of the assembly shown in FIG. 2;

FIG. 7 is a side elevational view of the cover shown in FIG. 3, and

FIG. 8 is a side elevational view of the assembly shown in FIG. 2.

The characteristic feature of my design resides in the combination on the hair dryer disclosed of the raised oval air intake eccentrically mounted on a tapered oval plate, together with a narrow recessed rear compartment and

a wider side recessed compartment containing the hose connection. The front and rear faces of the case follow the lines indicated in FIGS. 3-8 and are otherwise conventional.

I claim:

The ornamental design for a hair dryer, substantially as shown and described.
